UNITED STATES PATENT OFFICE

2,580,126

FOLDING TABLE

Paul H. Randolph, Miami, Fla.

Application December 9, 1947, Serial No. 790,481

1 Claim. (Cl. 311—84)

1

The present invention relates to new and useful improvements in tables and more particularly to a folding table designed for use out of doors.

An important object of the invention is to provide means connecting the legs at each end of the table to each other for uniform folding movement upwardly against the top of the table and connecting the legs to each other at their lower ends in a manner to brace the legs against lateral strain and also providing a longitudinally extending brace board between the lower ends of each pair of legs to lock the legs against folding movement as well as to brace the legs against longitudinal strain.

A still further object is to provide an axle journaled in the lower ends of a pair of the legs and to which one end of the brace board is permanently secured for folding upwardly against the table top by the folding of the legs.

A still further object is to provide a foldable table of simple and practical construction, which is strong and durable, attractive in appearance, relatively inexpensive to manufacture and otherwise well-adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the table in open position;

Figure 2 is an end elevational view;

Figure 3 is an enlarged bottom plan view with the table in folded position;

Figure 4 is an enlarged longitudinal sectional view taken substantially on the line 4—4 of Figure 2; and

Figure 5 is a longitudinal sectional view taken substantially on the line 5—5 of Figure 3 and showing the table in its folded position.

Referring now to the drawings in detail wherein for the purpose of illustration I have disclosed a preferred embodiment of the invention, the numeral 5 designates the table top generally and which is composed of transversely extending planks 6 secured in spaced parallel relation with respect to each other by means of a pair of longitudinally extending battens 7 through which screws or similar fastening devices 8 are inserted upwardly for penetration into the bottom of the planks to permanently secure the planks in position to the battens.

A pair of square-shaped shafts 9 extend trans-

2

versely between the battens adjacent the ends of the table, the shafts having rounded end portions 10 journaled in the batten.

A pair of legs 11 are secured to the end portions 10 of one of the shafts 9 outwardly of the battens and are held in position thereon by set screws or the like 12. The lower ends of the pair of legs 11 are secured to each other by a transversely extending axle 13 of square-shape in cross section and also having rounded end portions 14 journaled in the legs and having wheels 15 journaled on the outer ends of said rounded end portions 14. The wheels are secured in position on the axle by collars or washers 16 and set screws or the like 17.

A second pair of legs 20 are secured to the other shaft 9 inwardly of the batten 7 and secured to the rounded end portions of said shaft by set screws or the like 21. The lower ends of the legs 20 are connected to each other by a rigid transversely extending brace 22 and the lower ends of legs 20 are rounded as shown at 23 to facilitate sliding of the legs over the ground.

The central portion of axle 13 is notched as shown at 13a and in which is rigidly secured one end of a longitudinally extending brace board 24. The transverse brace 22 is also notched as shown at 25 and in which the other end of the brace board 24 is seated, said last-named end of the brace board having a pair of openings 26 therein for receiving a pair of pegs 27 extending downwardly from the notch in portion 25 of brace 22. The free end of the brace board 24 is held against the underside of brace 22 by pivoted catches 28 carried by the brace 22 and swingable into and out of a position underlying an adjacent side edge of the brace board 24.

The upper inner edges of legs 11 and 20 are rounded as shown at 29 to permit inward swinging movement of the legs into a folded position under the table top and the outer upper edges of the legs are formed with horizontal extensions or stops 30 abutting the under side of the top to prevent outward swinging movement of the legs.

The center plank 6 is formed with an opening 31 for receiving an umbrella staff (not shown) and the upper surface of brace board 24 is formed with a recess or socket 32 in which the lower end of the staff is seated to support an umbrella on the table.

When it is desired to fold the table, the catches 28 are swung outwardly to release the free end of brace board 24, the brace board swung downwardly and outwardly by rotating the axle 13 in

legs 11 from the full line position shown in Figure 4 to the dotted line position and the legs 11 and 20 swung upwardly against the table top. The folding of the legs 11 also swings the brace board 24 against the under side of the table top as shown in Figure 5.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A folding table including a top having a pair of spaced parallel battens at its underside, a pair of transverse shafts journaled in the battens at opposite ends of the table, a pair of legs pivoted on one shaft inwardly of the battens and a second pair of legs pivoted on the other shaft outwardly of the battens, said legs being foldable

against the underside of the top, a fixed cross brace connecting the lower ends of one pair of legs, a rotatable cross brace connecting the lower ends of the other pair of legs, a longitudinal brace fixed at one end to the rotatable cross brace for swinging into a folded position under the top together with the second pair of legs, said longitudinal brace having an opening at its free end, and a pin on the fixed cross brace engaged in said opening to lock the legs in open position.

PAUL H. RANDOLPH.
